Primary Examiner — Paul D Bohannon

(57) **CLAIM**

The ornamental design for an office chair as shown and described.

DESCRIPTION

1. Office chair

1.1 : Perspective

1.2 : Perspective

Significant distinguishing features: fastening of the side parts of the backrest from above through a jumper, a gap between the upholstery of the backrest and the seat, armrests—from a flattened tube with bends of the lower part inside; the connection of the sides from above with a jumper and the presence of free space between the upholstery of the backrest and the seat make the chair visually light; the curved armrests also add lightness to the design and increase the free seating area.
